UNITED STATES PATENT OFFICE

2,646,263

SMOKE AND SPARK ARRESTER FOR
CUPOLASMax W. Goldberg, West Bend, Wis., assignor to
Modern Equipment Company, Port Washington,
Wis., a corporation of Wisconsin

Application December 27, 1949, Serial No. 135,170

3 Claims. (Cl. 261—10)

1

This invention relates to improvements in smoke and spark arresters for cupolas.

During certain periods of operation, foundry cupolas emit rather large quantities of smoke. This is not only undesirable but, in certain areas, violates local smoke control ordinances. In addition, sparks commonly escape with the flue gases and create a fire hazard.

It is a general object of the present invention to provide efficient apparatus for removing sparks and smoke particles from the flue gases emitted from cupolas or similar heating devices.

A further object of the invention is to provide an improved smoke and spark arrester which advantageously puts to use heat of the flue gases which is normally wasted.

A further object of the invention is to provide an improved smoke and spark arrester which embodies the use of a vapor mist or steam to extinguish sparks and to remove dirt particles from the cupola flue gases.

A more specific object of the invention is to provide an improved smoke and spark arrester for a cupola wherein there is an enclosed chamber surrounding the upper end of the cupola which chamber is provided with an outlet, said arrester having an enclosed fluid receptacle positioned within said chamber and above the upper end of the cupola in a manner to be directly exposed to the flue gases emitted from the cupola, and there being nozzles around the periphery of said receptacle for discharging fluid from said receptacle across the path of the flue gases after the liquid in said receptacle has been heated by said flue gases.

A further object of the invention is to provide an improved smoke and spark arrester of the class described wherein a substantial amount of the fluid discharged from the receptacle is drained off as dirt carrying condensate, said arrester being so constructed that the dirt in the condensate is removed therefrom and said condensate is recirculated through the unit.

A further object of the invention is to provide a smoke and spark arrester of the class described wherein there is an elongated, horizontally extending discharge chamber communicating at one end with the main chamber and provided with a plurality of transverse screens, there being an elongated, vertical U-shaped discharge duct communicating with and depending from the other end of the discharge chamber and provided with an exhaust blower.

A further object of the invention is to provide an improved arrester of the class described wherein the discharge chamber and discharge

2

duct may be provided with a plurality of spaced, transversely extending screens.

A further object of the invention is to provide an improved smoke and spark arrester wherein there is means for removing foreign matter from the flue gases in the ducts by the use of fluid sprays which sprays reduce the volume of said gases, the size of the ducts being progressively reduced proportionately to said reduction in the volume of the gases so that the velocity of the gases is not substantially increased.

A further object of the invention is to provide an improved smoke and spark arrester having a downwardly extending duct portion and having an upwardly extending exhaust stack, there being a tank which affords communication between said members and there being an exhaust fan associated with said tank, the latter including a novel arrangement for washing the gases and for further reducing the volume thereof.

A further object of the invention is to provide in a device as above described having atomizing spray nozzles for directing fluid across the path of the flue gases and having a recirculating system for said nozzles, additional means for directing a spray of cooling water across the path of said flue gases, and means for utilizing overflow water from said cooling sprays to make up lost water content in said recirculating system.

A further object of the invention is to provide an improved arrester of the class described which is efficient in operation, relatively simple in construction, and which is otherwise well adapted for the purposes described.

With the above and other objects in view, the invention consists of the improved smoke and spark arrester, and all of its parts and combinations, as set forth in the claims, and all equivalents thereof.

In the drawings accompanying and forming a part of this specification, wherein is illustrated one complete embodiment of the preferred form of the invention, and wherein like characters of reference indicate the same parts in all of the views:

Fig. 1 is a fragmentary side view of a cupola with which one of the improved smoke and spark arresters is operatively associated, parts being broken away and shown in vertical section;

Fig. 2 is a transverse sectional view taken approximately along the line 2—2 of Fig. 1;

Fig. 3 is a fragmentary elevational view of the discharge duct and blower taken approximately along the line 3—3 of Fig. 2;

Fig. 4 is a fragmentary vertical sectional view

showing the cooling water tank, taken approximately on the line 4—4 of Fig. 5; and

Fig. 5 is a sectional view taken approximately on the line 5—5 of Fig. 4.

Referring more particularly to the drawing, the numeral 5 indicates a cupola mounted on a suitable support 6 and having an open upper end 7. The cupola 5 is provided with a blower 8 which communicates with an annular chamber 9 at the base of the cupola, commonly known as 10 the wind box.

Suitably mounted in enclosing relationship with the upper end of the cupola 5, as shown in Fig. 1, is a cylindrical chamber 10 having a centrally apertured circular bottom wall 11 and a 15 circular upper end wall 12. In addition, there is a discharge opening 13 in the side wall adjacent the upper end wall 12. The upper end of the cupola 5 projects through the aperture in the bottom wall 11 of the chamber 10 and terminates at a point spaced above said bottom wall.

Fixed to the upper end of the cupola and projecting upwardly from spaced points on the periphery thereof are a plurality of supporting legs 14. The legs 14 rigidly support an enclosed receptacle 15, which is preferably formed of a pair of conical shells joined at their bases, one being inverted and the other being upright. The receptacle 15 is positioned coaxially with respect to the upper end of the cupola 5 and is also positioned so that there is ample room for the passage of flue gases out of the upper end of the cupola. However, the position of the receptacle 15 is such that substantially all of the hot flue gases discharged from the cupola will wipe the undersurface of the receptacle 15 before said gases escape.

Mounted on the upper surface of the upper shell of the receptacle 15 and adjacent the periphery thereof are a plurality of circumferentially spaced nozzles 16 which communicate with the interior of the receptacle 15. A nozzle 17, similar to the nozzles 16, may be positioned at the apex of the upper shell of the receptacle 15. The nozzles are of any suitable construction capable of producing an atomizing spray.

Positioned adjacent the base 6 of the cupola 5 is a reservoir 18 provided with an intermediate partition 18' which terminates short of the upper margins of the reservoir 18, as shown. A drain pipe 19 communicates with the interior of the chamber 10 through the bottom plate 11 thereof and extends downwardly to the reservoir 18, as shown in Fig. 1, extending to near the bottom of said reservoir on one side of the partition 18'.

An electrically driven pump 20, preferably of the centrifugal type, has an inlet conduit 21 communicating with the interior of the reservoir 18 on the side of the partition opposite the pipe 19. A filter screen 21' may be positioned adjacent the open end of the inlet conduit 21. The outlet of the pump 20 extends into the interior of the receptacle 15 through a conduit 22 which conduit connects with the lower shell of the receptacle 15, at the apex thereof, as shown in Fig. 1. The conduit 22 may be equipped with an "on" and "off" valve 55 and with a valve 56 which may be adjusted to a predetermined setting to meter the flow.

An elongated discharge or exhaust chamber 23 projects horizontally from a side wall of the chamber 10 and communicates with said chamber through the opening 13. The discharge chamber 23 preferably has a horizontal top wall 24, vertical side walls 25 which flare as at 26, a

vertical end wall 28, and a bottom wall 29, the latter sloping slightly from the outer end toward the chamber 18, as shown in Fig. 1. A drain conduit 30 is in communication with the interior of the discharge chamber 23 adjacent the inner end of (the lowermost point in) the bottom wall 29, and the conduit 30 may be directed into the reservoir 18 along with the pipe 19, if desired.

Extending across the opening 13 may be a relatively coarse screen 31 to prevent the passage of relatively large particles with the flue gases, and extending transversely of the discharge chamber 23 may be a plurality of spaced relatively fine mesh screens 32.

Communicating with the interior of the receptacle 15 and projecting upwardly therefrom is an L-shaped conduit 33 having a relatively short horizontal extent directed toward the opening 13 and screen 31. The end of the L-shaped conduit 33 carries a nozzle 34. A Z-shaped conduit 35 communicates with the conduit 33 at the upper portion thereof. The conduit 35 extends through the screen 31, and terminates between the screen 31 and the innermost screen 32. The conduit 35 carries at its outer end a nozzle 36.

The bottom plate 29 of the discharge chamber 23 is formed adjacent its outer end with an opening 37. Extending vertically downwardly from the opening 37 is an elongated exhaust duct 38. The lower end of the exhaust duct 38 communicates with one end of the upper wall 41 of a generally horizontally extending duct or tank 39. The ducts 38 and 39 may be supported by suitable leg structure 40. The duct 39 has a pair of oppositely disposed vertical end walls 42 and 43, and a unitary side and bottom wall plate 44 which is generally U-shaped in cross section. The arcuate portion of the plate 44 slopes from the end adjacent the duct 38 downwardly toward the opposite end, and said plate 44 is formed with a drain connection 45 adjacent the lowermost end thereof.

A centrifugal blower 46 is mounted adjacent a side wall of the tank 39 at the end thereof opposite the duct 38. The blower 46 is provided with an inlet conduit 47 which extends into the interior of the tank 39 through the adjacent side wall portion thereof, as shown in Figs. 1 and 3. The blower 46 is driven by an electric motor 48 which may be mounted on a suitable pedestal 49 adjacent the blower. The discharge end of the blower 46 communicates with a vertically extending exhaust stack 50 which preferably projects upwardly beyond the roof of the building 55 in which the cupola is mounted. The duct 38 may have a plurality of spaced transversely extending screens 51 positioned therein. It is apparent that the ducts 38, 39 and 50 form a unitary, generally U-shaped exhaust duct.

Depending from the top of the tank 39 is an obliquely extending baffle 57 (see Fig. 4) having its lower edge terminating well above the bottom 44. A pair of atomizing spray nozzles 58 to which cold water is conducted by pipes 59 is adapted to direct a spray 60 toward and against the baffle 57. Valves 59' may be utilized to control the discharge from the nozzles 58.

Below the nozzles 58 is a pipe 61 which may be used as an overflow pipe to control the level of the liquid 60' in the bottom of the tank 39. This pipe may empty into the reservoir 18.

Additional cold water spray nozzles 62 and 63 may be employed in the exhaust stack 50, as shown in Fig. 1, to further cool the exhaust gases.

These nozzles may be independently controlled by valves 62' and 63' and may be supplied with cold water by a pipe 64 leading from a suitable source of water under pressure.

The operation of the improved smoke and spark arrester is substantially as follows:

The pump 20 pumps water under pressure from the reservoir 18 through the conduits 21 and 22 into the closed receptacle 15. The regulating valve 56 may be adjusted to keep the cone substantially filled with water. The hot flue gases being discharged from the open upper end 7 of the cupola 5 wipe the bottom surface of the receptacle 15 and raise the temperature of the water therein to the boiling point or very near the boiling point. The pressure within the receptacle 15, created by the pump, causes the water to be discharged from the nozzles 16 and 17, 34 and 36. Inasmuch as the nozzles are atomizing nozzles, the water is broken up into a fine mist so that it is flashed into steam almost instantly upon coming in contact with the hot gases in the chamber 10. From Fig. 2 it will be noted that as the flue gases pass upwardly around the periphery of the receptacle 15 they must pass through the mist and steam emitted from the nozzles 16 and 17.

The mist or steam emitted from the nozzles extinguishes any sparks and carries with it the dirt particles in the flue gases. As the steam contacts the walls of the chamber 10 and the walls of the chamber 23, the steam is condensed and flows down the side walls of said chambers to the bottom plates and thence out of the drain conduits 19 and 30.

Referring to Fig. 1, the cone 15 is spaced above the cupola a sufficient distance so that the annular space α is greater than the area of the opening at the upper end of the cupola 5 proper. With this arrangement there is no retarding of the upward flow of the flue gases. The inclined bottom of the receptacle 15 directs the hot flue gases outwardly and upwardly to aid in their movement and to insure passage through the steam and mist.

The condensate is returned to the reservoir 18 by the conduits 19 and 30, and the dirt particles therein will settle to the bottom of the reservoir 18 adjacent the lower end of the pipe 19. The condensate overflows the partition 18' and, after being filtered by the screen 21', is recirculated by the pump 20. The dirt particles separated from the flue gases by the screens 31, 32, and 52 are washed off said screens by condensate which collects thereon and runs down said screens carrying the dirt particles with it toward the drain pipes.

Referring to Fig. 2, it is apparent that the flared side wall portions 26 of the discharge chamber 23 provide an enlarged throat so that there is plenty of room for the hot gases, of expanded volume, to leave the chamber 10. The spray from the nozzle 36 which is in the form of a mist, rather than in the form of steam, condenses steam rising with the gases and by means of its cooling effect reduces the volume of the gases sufficiently so that they can be accommodated in the smaller duct 38 by the time the gases have reached this duct. The reduction in the duct size is approximately proportional to the reduction in the volume of the gases so that velocity of the gases is maintained substantially constant with no substantial increase. Too high a velocity is undesirable because foreign material can be removed more efficiently from the flue gases when the gases are not travelling too fast.

The conical form of the top of the receptacle 15 allows any condensate which falls thereon to flow toward the bottom trough 11.

The suction fan 46 keeps the gases moving and pulls them downwardly through the duct 38 into the top of the tank 39, as shown in Fig. 4. Here the gases must pass through the cold water sprays 60 where the volume is again reduced and where any further dirt is washed out of the gases. In addition, the gases must pass beneath the lower edge 65 of the baffle 51, through the curtain of water 60'' which is cascading from said lower edge toward the bottom of the tank 39. The water at 60'' therefore, again washes the gases and again cools the same. The area of the space between the lower edge of the baffle 65 and the surface of the water 60' in the bottom of the tank must be greater than the area of the inlet 66 to the suction pump 46. After the gases leave the pump they are blown upwardly in the exhaust conduit 50 where they may be again sprayed with cold water by the spray nozzles 62 and 63 (Fig. 1). It is to be noted from Figs. 1 and 5 that the fan intake opening 66 is elongated and located intermediate the width of the tank 39 so that the gases from the duct 38 will pass through the curtain 60'' across substantially the full width thereof.

By having the gases pass beneath the lower edge 65 of the baffle 51 of Fig. 4 they are not only cooled by the curtain of water 60'', but are also cooled by sweeping the surface of the body of water 60'.

The water from the sprays 60 which is returned to the reservoir 18 through the pipe 61 provides make up water to replace that lost out of the stack 50.

The improved smoke and spark arresting apparatus, in addition to extinguishing all sparks, effectively removes substantially all solid particles from the flue gases emitted from the cupola 5.

The improved arrester will operate satisfactorily without the use of the screens, but experience has shown that increased efficiency results from the use thereof. Also, it is obvious that the apparatus will function satisfactorily whether or not the condensate is recirculated, or if means other than the reservoir shown is used to separate the dirt particles from the condensate.

Various changes and modifications may be made without departing from the spirit of the invention, and all of such changes are contemplated, as may come within the scope of the claims.

What I claim is:

1. In a smoke and spark arrester for a cupola wherein said cupola has an open upper end; an enclosure surrounding said upper end of the cupola and having an exhaust opening covered with a screen; an enclosed receptacle mounted within said enclosure at the upper end of the cupola and in a position to be wiped by the flue gases emitted from the cupola; means for introducing a liquid into said receptacle; at least one nozzle for discharging fluid from said receptacle into said enclosure after the liquid therein has been heated by said flue gases; an exhaust chamber communicating at one end with the exhaust opening of said enclosure and having its own exhaust opening at the opposite end thereof; nozzles connected to said receptacle and positioned to discharge heated fluid from said receptacle against said exhaust opening screen and into said exhaust chamber; means for draining said exhaust chamber; a plurality of spaced transversely extending screens mounted in said ex-

haust chamber; and an exhaust blower having its inlet communicating with the interior of said exhaust chamber through the exhaust opening of the latter.

2. In a smoke and spark arrester for a cupola wherein said cupola has an open upper end; an enclosure surrounding said upper end of the cupola and having an exhaust opening near the top thereof; an enclosed receptacle mounted within said enclosure at the upper end of the cupola and in a position to be wiped by the flue gases emitted from the cupola; means for introducing a liquid into said receptacle; at least one nozzle for discharging fluid from said receptacle into said enclosure after the liquid therein has been heated by said flue gases; a generally horizontally extending exhaust chamber near the top of said enclosure and communicating at one end with the exhaust opening of said enclosure and having its own exhaust opening at the opposite end thereof; a nozzle connected to said receptacle and positioned to discharge fluid from said receptacle into said exhaust chamber; means for draining said exhaust chamber; a vertically extending elongated generally U-shaped exhaust duct having a vertically extending leg portion thereof depending from said exhaust chamber and communicating with the interior of said exhaust chamber through the exhaust opening thereof; and a blower in said exhaust duct.

3. In a smoke and spark arrester for a cupola wherein said cupola has an open upper end; an enclosure surrounding said upper end of the cupola and having an exhaust opening covered with a screen; an enclosed circular receptacle mounted within said enclosure at the upper end of the cupola and spaced from the sides of said enclosure in a position to be wiped by the flue gases emitted from the cupola; means for introducing a liquid into said receptacle; a plurality of nozzles adjacent the periphery of said

10
